UNITED STATES PATENT OFFICE.

JOHN LOGAN AND MILTON H. STEVENS, OF WALTHAM, MASSACHUSETTS.

APPARATUS FOR HARDENING STRIPS OF METAL.

SPECIFICATION forming part of Letters Patent No. 484,968, dated October 25, 1892.

Application filed October 26, 1891. Serial No. 409,860. (No model.)

To all whom it may concern.

Be it known that we, JOHN LOGAN and MILTON H. STEVENS, of Waltham, in the county of Middlesex and State of Massachusetts, have 5 invented certain new and useful Improvements in Apparatus for Hardening Strips of Metal, of which the following is a specification.

Our invention has for its object the heating of long strips of metal—such as narrow 10 steel ribbon—used for watch or clock springs preliminary to its subjection to a liquid bath, as of oil or water. It will be understood that in order to secure a positive uniformity in the hardness of the metal in its entire length, it must have a uniform degree of heat at the 15 instant of its subjection to the chilling-bath of liquid, which must also be maintained at a constant temperature. Formerly in the manufacture of watch-mainsprings it was cus- 20 tomary to cut the metal strips into lengths a trifle in excess of that of a finished spring, and when in readiness for the process of hardening they were carefully coiled in a flat in- 25 volute spiral, the successive coils being sepa- rated from each other by the intervention of small wires, which also served to bind and hold the completed coil in place. These coils 30 were then placed upon a sort of table or rack, which was capable of being revolved or turned upon a stud or pin affixed at the end of a long 35 handle of iron. This was then placed in a large muffle or furnace, ordinarily heated by coal or coke and by means of an iron rod, the above-mentioned table was at intervals 40 moved around for the purpose of securing, so far as possible, a uniformity of heat in all portions of the coil of metal. When suffi- 45 ciently heated, the whole was removed from the furnace and the coil plunged into a bath of tallow, oil, or water, or any suitable com- 50 pound, and when cool the binding-wires were removed and the various lengths of steel sep- arated. If the entire lot had by carefulness and skill been evenly hardened, it would be found that the strips near the center of the coil had quite a different curve from those near the outside of the coil and were much more likely to be broken while in their state of brittleness.

50 A great improvement in the foregoing method was embodied in the patent of John Logan, No. 297,610, of April 29, 1884, which

consisted in tightly coiling long strips of the steel and inclosing them in round boxes or closed muffles, the outer end of the strip pro- 55 jecting through an opening in the periphery of the box. This muffle was then carefully heated in any suitable furnace, preferably using gas as a fuel, and when properly heated the entire strip was withdrawn from the 60 muffle into and through the cooling-bath, be- 65 ing wound upon any suitable drum or bobbin.

Our invention is an improvement upon the last-mentioned process, and by it the coiling of the several steel strips is rendered need- 70 less, as is also the use of the muffles. A uni- 75 formity of heat is also secured, the hardening process greatly expedited, and a uniformity in quality, as well as a ready adaptation to large or small stock, is provided for. To this end we secure the proper heating of the steel strips by a rolling contact with the periphery of two or more revolving drums or wheels, which are maintained at the desired degree of heat by flames of gas, which impinge on 75 the interior surface of the hollow drums or wheels, as shown in the accompanying drawings, in which—

Figure 1 is an end elevation of part of the contrivance. Fig. 2 is a longitudinal central 80 section of the same. Fig. 3 is a transverse section of the same, showing, also, partially in section, the chilling-bath appliances.

A represents a platform or carriage mounted on wheels *a*, fitted to run on an iron track 85 or way *b*.

B represents a suitable frame, in which are mounted two shafts or arbors *C* and *C'*, one of which is preferably located over the other. One of these shafts carries a worm-gear *c*, 90 which is driven by a worm *d*. The second shaft receives motion from the first, either by means of spur-gears or a crossed belt, as shown herein. On adjacent ends of shafts are mounted hollow drums *D* and *D'*, which 95 are removably affixed to the shafts. In the interior of each of the drums are located compound gas-burners *E* and *E'*.

F is a suitable covering or housing, preferably lined with fire-brick and secured to the 100 movable carriage.

F' is a similar housing firmly fixed to the iron track.

G is a gas-pipe connecting with burners *E*

and E'. H is a wind or an air-blast pipe leading to the same burner.

I represents a spool or bobbin containing the steel strips to be hardened.

5 K is a guide-roll affixed to housing F.

L represents the tank or oil-bath, having an inclined apron l, in which are suitable guides.

N is a constant stream of oil flowing upon 10 the apron l, thence into the tank, whence it is carried by an overflow-pipe f to a suitable cooling-chamber, from which it is again drawn or forced through a pipe f' by means of a pump, of any known construction adapted to 15 the purpose, and again discharged upon the apron.

O is the steel strip, moving in the directions indicated by the arrows. These strips are joined end to end, so that when once started 20 the strip may be kept in constant motion until the bobbin I is emptied. It will be observed that while the housing F' is stationary F is movable, being carried by the carriage. This arrangement readily allows the 25 removal or replacing of the drums and also gives convenient access to the burners.

This description of the machine renders very apparent its mode of operation, which is briefly as follows: The movable carriage is 30 rolled back from the fixed housing, exposing the gas-burners, which are then lighted, and the proper combination of air and gas adjusted by means of the ordinary controlling valves or cocks. The carriage is then moved 35 back into place and the drums put in motion, as previously described. The steady revolution of the drums insures a uniform distribution of heat over the entire circumference of the drums, and when they have 40 been brought to the desired degree of heat the carriage is again moved back a short distance, and the strip of steel to be hardened is passed down under the lower drum and across and over the top one, thence through the oil- 45 stream and between guide-rolls and into and through the oil-bath and wound upon another reel or bobbin. The speed of the revolving heating-drums will of course govern the process of the wire, and this will be so regulated

as to insure a proper degree of heat, which 50 will be absorbed by its contact with the moving surface of the drums. The amount of heat can also be governed by manipulation of the gas and air valves. It will be apparent that the heavier the strip the slower 55 must it be moved or the greater must be the heat of the drums. The speed of the latter may be varied by any convenient means, as by the employment of the Evans friction-cones. By omitting the chilling-bath the 60 same apparatus may be used for the process of annealing, and we do not limit ourselves to two drums or burners, as any number may be used without departing from the spirit of the invention. 65

Having now described our invention, we desire to claim—

1. The combination, with a divided housing provided with openings for the passage of a strip or ribbon of material, of one or 70 more revolving drums, each having a burner within it arranged within the housing, as set forth.

2. The combination, with a divided housing provided with openings for the passage 75 of a strip or ribbon of material, of one or more revolving drums, each having a burner within it arranged within the housing, and a movable carriage with which a divided part of the housing is connected, as set forth. 80

3. The combination, with a divided housing provided with openings for the passage of a strip or ribbon of material, of one or 85 more revolving drums, each having a burner within it arranged within the housing, an apron or table over which the strip of material passes, and a pipe for discharging a continuous stream of oil or other liquid upon the material, as set forth.

In testimony whereof we have signed our 90 names to this specification, in the presence of two subscribing witnesses, this 10th day of October, A. D. 1891.

JOHN LOGAN.

MILTON H. STEVENS.
